CLAIM

The ornamental design for the side panel for readily disassembled instrument housing, substantially as shown and described.

DESCRIPTION

FIG. 1 is a front elevation view of the side panel showing my new design;

FIG. 2 is a bottom plan view of the side panel shown in FIG. 1;

FIG. 3 is a rear elevation view of the side panel shown in FIGS. 1-3;

FIG. 4 is an end elevation view of the side panel shown in FIGS. 1-3; and

FIG. 5 is a cross-sectional view taken through FIG. 1 along the line 5-5.

Fig. 1.
